CLAIM

The ornamental design for a capsule for containing washing products, as shown and described.

DESCRIPTION

FIG. 1 is a perspective view of a capsule for containing washing products of the present invention;

FIG. 2 is a front view of the capsule for containing washing products of FIG. 1;

FIG. 3 is a side view of the capsule for containing washing products of FIG. 1;

FIG. 4 is a back view of the capsule for containing washing products of FIG. 1;

FIG. 5 is the other side view of the capsule for containing washing products of FIG. 1;

FIG. 6 is a top view of the capsule for containing washing products of FIG. 1; and,

FIG. 7 is a bottom view of the capsule for containing washing products of FIG. 1.

The broken lines are included for the purpose of illustrating a portion of the capsule for containing washing products that forms no part of the claimed design.

1 Claim, 7 Drawing Sheets
